UNITED STATES PATENT OFFICE

128,162

DESIGN FOR A CARD TRICK DEVICE

Kenneth S. Franke, New York, N. Y.

Application December 7, 1940, Serial No. 97,155

Term of patent 3½ years

To all whom it may concern:

Be it known that I, Kenneth S. Franke, a citizen of the United States, residing at New York, in the county of New York and State of New York, have invented a new, original, and ornamental Design for a Card Trick Device, of which the following is a specification, reference being had to the accompanying drawing, forming a part thereof.

In the drawing Figure 1 is a view in perspective, showing the back, one side and top of the device and Figure 2 is a front elevation thereof.

I claim:

The ornamental design for a card trick device, as shown.

KENNETH S. FRANKE.
